CINEMATOGRAPHIC CAMERA

Bernhard Jablonski, Musberg, Germany, assignor to
Robert Bosch Elektronik und Photokino G.m.b.H.,
Stuttgart-Unterturkheim, Germany

Filed June 20, 1966, Ser. No. 2,753

Term of patent 7 years

(Cl. D61—1)

FIG. 1

FIG. 2

FIG. 3

FIG. 4

FIG. 5

FIG. 6

FIG. 7

FIG. 8

FIG. 1 is a side elevational view of a cinematographic camera, showing my new design;
FIG. 2 is an opposite side elevational view;
FIG. 3 is a top plan view;
FIG. 4 is a bottom plan view;
FIG. 5 is a front elevational view;
FIG. 6 is a rear elevational view;
FIG. 7 is a rear and side perspective view; and
FIG. 8 is a rear and opposite side perspective view thereof.

The dominant features of my new design are shown in solid lines in the drawing. The drawing figures are shaded to indicate contrast in appearance.

I claim:

The ornamental design for a cinematographic camera, substantially as shown and described.
